Falter Eige,
Barrett & Thuman,
Attorneys

UNITED STATES PATENT OFFICE.

FALTEN EIGE, OF TORONTO, CANADA, ASSIGNOR TO C. A. DUNHAM COMPANY, OF MARSHALLTOWN, IOWA, A CORPORATION OF IOWA.

BUCKET TRAP.

Application filed November 12, 1923. Serial No. 674,329.

My invention relates to bucket traps of the type adapted for the removal of condensate from fixtures and steam lines where high pressure steam is used and where large amounts of condensate accumulate, although it is also suitable for use where low pressure steam is employed, as well as for the removal of water or other liquid from any receptacle which contains air or other gas under pressure.

It is the principal object of my invention to provide a new and improved form and arrangement of parts, with particular reference to the form of the bucket, by which the closing of the valve for stopping the intermittent discharge from the trap is effected very quickly and positively; and to improve devices of this type in sundry details hereinafter pointed out.

The preferred means by which I have accomplished my several objects, are illustrated in the drawing and are hereinafter specifically described. That which I believe to be new and desire to cover by this application is set forth in the claim.

In the drawing:

Fig. 1 is a central vertical section through by improved trap.

Fig. 2 is a perspective view of the valve member; and

Fig. 3 is a perspective view, partly in section, showing the form of the valve seat.

Referring to the several figures of the drawing, in which corresponding parts are indicated by the same reference characters, 10 indicates a casing closed at its upper end by a cover plate 11, the two together comprising a closed tank, with a pipe 12 leading into the tank at one side for delivering condensate to the tank from some container for steam or other fluid under pressure. A baffle plate 13 depends from the cover plate 11 opposite the opening of the pipe 12 into the tank. The cover plate 11 is provided with a discharge port in which there is mounted by means of screw threads a cage 14 for the purpose hereinafter described. A cap 15 is removably secured over the cage 14, and a transversely disposed duct 16 is provided in the cover plate 11 in communication with the interior of the cap 15 and having connected thereto a pipe 17 for the condensate discharged from the tank. The casing 10, the cover plate 11, and the cap 15, are preferably made in the form of castings, and are removably secured together in any appropriate manner.

Within the closed tank comprising the casing 10 and the cover plate 11, there is pivotally mounted a bucket 18, which is also preferably in the form of a casting, the bucket 18 having a downward extension 19 at one side thereof adjacent to the pivotal axis 20 upon which the bucket is pivotally mounted on a horizontal axis upon arms 21 depending from the baffle plate 13. A discharge tube 22, which in the construction shown is formed integrally with the cover plate 11 extends downwardly about the discharge port in the cover plate 11 to substantially the lowermost point within the downward depression 19 of the bucket, being open at its lower end. A valve rod 23 is pivotally connected with the bucket 18 within the downward projection 19, such connection being effected by the use of a bolt 24 through which the valve rod 23 is pivotally connected. The valve rod 23 extends upwardly through the discharge tube 22 and is provided at its upper end with a sleeve 25 secured thereon by means of screw threads, a lock nut 26 being provided upon the valve rod 23 for tightening the sleeve 25 in adjusted position thereon. The sleeve 25 is made in the form of a casting, having pins 27 secured in radial position thereon for holding the sleeve 25 in centered position with respect to the cage 14 into which the sleeve extends. In the upper end of the sleeve 25, there is removably secured a valve 28 which is held in position by a pin 29 extending loosely through openings in the valve and in the sides of the sleeve, the pin 29 being normally held in position by the cage 14. The valve 28 is tapered at both ends for proper effective engagement at either end with a valve seat 30 which is removably secured within the upper end of the cage 14 by means of a screw threaded sleeve 31. As is clearly shown in Fig. 3, the seat member 30 is similarly formed on its opposite faces, so that the seat 30 is reversible for effective operation in either of its two adjusted positions. The construction is such that when the valve 28 in its raised position engages the opening through the seat member 30, the discharge port is effectively closed.

With the tank connected up in the manner above described so as to have a fluid

pressure upon the interior of the tank, and with the bucket 18 containing only a small quantity of water as illustrated in Fig. 1, and being accordingly held by buoyancy in its raised position as shown in solid lines in said Fig. 1, the tank receives the condensate from the pipes, the engagement of the valve 28 with its seat member 30 serving to limit the upward movement of the bucket 18. When the water in the tank reaches a sufficiently high level, it overflows into the bucket 18. When the level of the water in the bucket 18 approaches the level of the water within the tank on the outside of the bucket, the buoyancy of the bucket is gradually decreased and finally overcome, whereupon the bucket sinks to the position shown in dotted lines in said figure. Upon this movement of the bucket, the valve 28 is of course moved downwardly away from its seat, whereupon the pressure within the tank forces the water upwardly through the discharge tube 22 and out through the pipe 17. When the water in the tank has thus been lowered to the level defined by the upper edge of the bucket 18 at the point 32 in Fig. 1, the water can then no longer be lowered in the space in the tank about the bucket 18, but the level of the water within the bucket continues to go downwardly. When thereafter the level of the water within the bucket reaches substantially the same level as that of the bottom 33 of the bucket, as shown in dotted lines in Fig. 1, the buoyancy of the bucket again overcomes the weight of the bucket and the contained water so as to cause the bucket to rise. Inasmuch as the stop 34 carried by the casing 10 prevents the bottom 33 of the bucket 18 from moving downwardly beyond a substantially horizontal position, it will be understood that at substantially the start of the upward movement of the bucket 18 the entire liquid contents of the bucket is caused to gather quickly within the downward extension 19. This shifting of the water within the bucket 18 toward the pivotal axis 20 of the bucket increases quite materially the effective buoyancy of the bucket, with the result that the bucket rises very quickly and positively to its uppermost position as shown in solid lines in Fig. 1, serving to effect a quick and positive closing of the valve for stopping the escape of the water from the tank.

So far as I am aware, I am the first in

the art to provide a bucket of this type having a downward extension into which the water gathers quickly at the start of the upward movement of the bucket by reason of the fact that the stop means has been provided serving to prevent the bucket from moving downwardly beyond the position at which the main portion of the bottom stands at a substantially horizontal position, and whereby it is assured that the lower end of the discharge tube always remains sealed by a body of water in the downward depression of the bucket.

While I prefer to employ the form of construction illustrated in the drawing and above described, it will be understood that I do not wish to limit myself to the use of the detailed form of construction described except so far as such detailed construction may be specifically claimed, inasmuch as it is evident that many changes might be made in the construction without departing from the spirit of my invention.

I claim:

A trap comprising a closed tank, a long shallow bucket open at the top and having a downward extension adjacent one end, the bucket being pivoted in the tank on a horizontal axis adjacent the bottom of the downward extension, a discharge tube depending into the bucket and opening at the bottom into the downward extension below the level of the remaining portion of the bottom of the bucket whereby a water seal is provided for the discharge tube in all positions of the bucket, a valve for opening and closing said discharge tube, connections between the bucket and valve for opening the valve by the downward movement of the bucket and closing the valve when the bucket moves upwardly, and means for limiting the downward movement of the bucket at a point where the bottom of the major portion of the bucket is substantially horizontal so that the major portion of the bucket may be entirely drained of its liquid contents through the discharge tube, the upper open top of the bucket being inclined to a point considerably below the maximum liquid level in the tank when the bucket is in its lowered position whereby a substantial portion of the tank contents is drained along with the contents of the bucket.

FALTEN EIGE.
